UNITED STATES PATENT OFFICE.

SAMUEL T. KURTZ, OF SAN DIEGO, CALIFORNIA.

GRAPPLING APPARATUS.

Application filed June 28, 1924. Serial No. 723,043.

To all whom it may concern:

Be it known that I, SAMUEL T. KURTZ, a citizen of the United States, residing at San Diego, in the county of San Diego and State 5 of California, have invented a certain new and useful Grappling Apparatus, of which the following is a specification.

My invention relates to a grappling apparatus, more particularly adapted for use 10 in removing articles from the bottoms of rivers or bodies of water, or from holes, wells or the like, and the objects of my invention are: First, to provide a grappling apparatus of this class in which the article 15 or object which it is attempted to grapple trips the apparatus and causes the apparatus to seize or grab said article or object; second, to provide an apparatus of this class which is spring actuated and in which the 20 supporting means is so connected with the grappling apparatus that the raising of the load causes the grappling apparatus to engage the article raised more tightly; third, to provide an apparatus of this class in which 25 the tripping member, as soon as the apparatus is tripped, is thrown out of engagement with the article and upwardly out of the way; fourth, to provide an apparatus of this class which may be extended and op- 30 erated at a long distance from the operator; fifth, to provide an apparatus of this class which is applicable for use in water or in any place that is ordinarily inaccessible; sixth, to provide a novelly constructed grap- 35 pling device, and seventh, to provide an apparatus of this class which is very simple and economical of construction, durable, ef- ficient, automatic in its action and which 40 will not readily deteriorate or get out of order.

With these and other objects in view, as will appear hereinafter, my invention consists of certain novel features of construction, combination and arrangement of parts 45 and portions, as will be hereinafter described in detail and particularly set forth in the appended claims, reference being had to the accompanying drawings and to the characters of reference thereon, which form a part 50 of this application, in which:

Figure 1 is a side elevational view of my grappling apparatus shown set ready for

use; Fig. 2 is a side elevational view at a right angle thereto, showing a portion broken away to facilitate the illustration; 55 Fig. 3 is a side elevational view similar to that of Fig. 1, showing the device after it is sprung and engaging an article to be raised, and Fig. 4 is a transverse sectional view through 4—4 of Fig. 1. 60

Like characters of reference refer to similar parts and portions throughout the several views of the drawings.

The grappling members 1 and 2, trip member 3, links 4, springs 5, main spring 6, 65 cables 7 and 8, and cable guide member 9, constitute the principal parts and portions of my grappling apparatus. The grappling members 1 and 2 are preferably made of metal in the form of a bar. They are each 70 provided on their normally lower ends with inwardly extending engaging points 1^a and 2^a. They are also provided with lugs 1^b and 2^b with which the ends of the links 4 are pivotally connected. They are also pro- 75 vided with lugs 1^c and 2^c with which the one ends of the cables are connected. They are also provided with lugs 1^d and 2^d, with which the opposite ends of the spring 6 are connected, and they are provided intermediate their ends with large double bifurcated lugs 1^e and 2^e by means of which they are 80 pivotally connected together by means of a bolt 10. This bolt also supports the mem- 85 ber 9 which is provided with holes 9^b there- in adapted for guides for the cables 7 and 8 which pass through said hole, supported by these cables 7 and 8. Reciprocally mount- 90 ed in the member 9 is the trip member 3 by means of a hole positioned centrally in said member 9. This trip member 3 is pro- 95 vided near its lower end with lugs 3^a to which are pivotally connected the inner ends of the link members 4. This trip mem- ber is also provided with lugs 3^b in which the one ends of the springs 5 are connected and the opposite ends of said springs are 100 connected to the extended end of the bolt 10, as shown best in Fig. 2 of the drawings. The upper end of the member 3 is bifur- cated, and in the space between the bifur- cated portion is mounted the main spring 6, which is preferably a plate spring, and it is secured at its opposite ends to the mem-

bers 1 and 2 by means of the lugs 1^a and 2^a. This member 3 is provided with a pair of flanged lugs 3^c, the flanges of which are adapted to engage the upper ends of the members 1 and 2 and form a latch for holding them in close relation at their upper ends and therefore their lower or grappling ends spread apart, as shown best in Fig. 1 of the drawings. This member 3 is hollow and extends upwardly some distance, and in the hollow portion are positioned the cables 7 and 8 which serve as supports for the grappling device.

The operation of the grappling apparatus is as follows: The apparatus is lowered on the cables 7 and 8 so that the lower ends 1^a and 2^a are on the opposite sides of the object which it is desired to raise and the extended end of the tripping member 3 engages the object and raises the tripping member relatively to the members 1 and 2, which causes the portions 3^c to be disengaged from the upper ends of the members 1 and 2, whereupon the spring 6 thrusts the upper ends of said members apart and the lower ends of said members together. At the same time the spring 5 thrusts the tripping member upwardly so that the grappling members engage the object to be raised at the lower end, as shown best in Fig. 3 of the drawings.

It will be noted that when the object is gripped in this manner, the cables 7 and 8 tend to draw the lower ends of the members 1 and 2 together because they are connected below the pivotal mounting of said members, therefore the load tends to draw the grappling members together at the lower ends against the object to be raised.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent, is:

1. In a grappling apparatus, a pair of members pivotally connected together intermediate their ends, a spring member tending to hold said members apart at their upper ends, latch means adapted to hold said members together against the action of said spring and provided with an extended portion extending between the opposite ends of said members, and cable means connected to said grappling members below their pivotal connection.

2. In a grappling apparatus, a pair of members pivotally connected together intermediate their ends, a spring member tend-

ing to hold said members apart at their upper ends, latch means adapted to hold said members together against the action of said spring and provided with an extended portion extending between the opposite ends of said members, cable means connected to said grappling members below their pivotal connection, and a spring in connection with said trip member adapted to raise said trip member when it is released from the latch means.

3. In a grappling apparatus, a pair of grappling bars pivotally connected intermediate their ends, a spring connected to the upper ends of said grappling bars tending to spread said bars apart at their upper ends, combined trip and latch means tending to hold the upper ends of said members together and adapted to engage an object for releasing said latch means, and means extending between said grappling members for supporting said grappling members connected to said grappling members below their pivotal connection.

4. In a grappling apparatus, a pair of grappling bars pivotally connected together intermediate their ends, spring means tending to hold said grappling members together at their lower ends, latch means adapted to engage said members for holding them apart at their lower ends, trip means in connection with said latch means for releasing said latch means from said grappling members, and means extending between said grappling members connected to said grappling members below the pivotal connection for supporting said grappling members tending to draw said grappling members together at their lower ends.

5. In a grappling apparatus, a pair of grappling members positioned in an approximately vertical position pivotally connected together intermediate their ends, a combined trip and latch member reciprocably mounted between said grappling members, the latch portion adapted to engage the upper ends of said grappling members and hold them in certain relation to each other, a spring connected to the upper ends of said grappling members tending to spread the upper ends of said members apart, and a spring secured to said trip member and supported in relation to said grappling members tending to raise said trip member.

6. In a grappling apparatus, a pair of grappling members positioned in an approximately vertical position pivotally connected together intermediate their ends, a combined trip and latch member reciprocably mounted between said grappling members, the latch portion adapted to engage the upper ends of said grappling members and hold them in certain relation to each other, a spring connected to the upper ends

of said grappling members tending to spread the upper ends of said members apart, a spring secured to said trip member and supported in relation to said grappling members tending to raise said trip member, and cable means connected to said grappling members below their pivotal mounting at

their inner sides and extending upwardly and supported by said trip member.

In testimony whereof, I have hereunto set 10 my hand at San Diego, California, this 14th day of June, 1924.

SAMUEL T. KURTZ.
